UNITED STATES PATENT OFFICE

2,285,861

MINING MACHINE

Robert K. Jeffrey, Columbus, Ohio, and Lewis E. Mitchell, deceased, late of Columbus, Ohio, by Richard D. Nichols, administrator, Columbus, Ohio, assignors to The Jeffrey Manufacturing Company, a corporation of Ohio

Original application May 6, 1938, Serial No. 206,448, now Patent No. 2,263,779, dated November 25, 1941. Divided and this application November 4, 1940, Serial No. 364,323

5 Claims. (Cl. 262—28)

This invention relates to a mining machine and particularly to the construction of an electric motor thereof which drives the mining mechanism, such as a kerf cutting mechanism.

An object of the invention is to provide an improved motor construction which is of the totally enclosed type and particularly to provide improved means for cooling such a motor.

A further object of the invention is to provide a motor structure which cooperates to form an integral part of a supplementary frame.

Still another object of the invention is to provide improved mechanism for adjusting the supplemental frame, including a motor casing or housing, to adjust a mining mechanism, such as a kerf cutter.

Other objects of the invention will appear hereinafter, the novel features and combinations being set forth in the appended claims.

This application is a division of our application Serial No. 206,448, filed May 6, 1938, for an Improvement in mining machines, which matured into Patent No. 2,263,779, Nov. 25, 1941.

In the accompanying drawings,

Fig. 1 is a diagrammatic plan view showing a mining machine incorporating the structure of our invention;

Fig. 2 is an enlarged plan view showing the central portion of the mining machine of Fig. 1;

Fig. 3 is a sectional plan view through the electric motor forming part of the invention herein claimed; and

Fig. 4 is a transverse sectional elevational view of an elevating hydraulic piston motor taken on the line 4—4 of Fig. 2 looking in the direction of the arrows.

In Fig. 1 of the drawings, there is illustrated diagrammatically a mining machine which incorporates the features of our invention herein claimed. The mining machine is disclosed in full detail in our parent application above identified, of which this application is a division, and so no attempt will be made to describe it in detail except as to details forming the subject matter herein claimed.

Said mining machine includes a truck 45 which supports a turntable 71 upon which is mounted for adjustment in a vertical plane a supplemental frame 100 which has a forwardly extending neck 109 carrying a turnover head mechanism 159 which provides for various adjustments of kerf cutting mechanism 160.

Extending rearwardly from and supported by the truck 45 is a platform 545 which carries a considerable amount of mechanism which per se

is not pertinent to the invention herein claimed.

The turntable 71 is mounted upon the truck 45 for swinging movement in a horizontal plane or about an upright axis (see Fig. 2). Said turntable 71 (Fig. 2) is formed by a top plate 72 which has attached at its center a casting or pedestal and carries at its periphery a large race 76 which cooperates with a plurality of balls 77 and an outside large race 78 carried by the top plate 79 of the truck 45 to form an anti-friction mounting for said turntable 71 upon said truck 45. The outer peripheral edge of the top plate 72 is provided with a downwardly extending flange 93 adapted to protect the bearing members and to prevent entrance of dirt to the bearing surfaces.

It is to be noted that the balls 77 are held in shearing relation between the races 76 and 78 and thus prevent both upward and downward movement of the turntable 71 with respect to the truck 45 while providing an anti-friction pivotal connection between them for relative movement about a vertical or upright axis. The bearing area provided by the large number of balls 77 is sufficient to provide for this particular type of mounting.

To provide for the swinging movement of the turntable 71 about its upright axis with respect to the truck 45, we provide a pair of hydraulic piston motors 82 and 83 which are fully disclosed in our parent case, above identified.

As disclosed completely in said parent application, the two hydraulic piston motors 82 and 83 are always operated together and in reverse directions so that a very powerful and equalizing force will be transmitted to the turntable 71 to swing it.

As best seen in Figs. 1, 2 and 4 of the drawings, there is mounted upon the turntable 71 for movement about a horizontal axis a supplementary frame 100 formed by a rigid motor casing 101 within which is housed an electric motor for driving the kerf cutting mechanism 160. Adjacent its rear bottom portion the motor casing 101 is provided with side journal bearings 102, 102 which pivotally support said supplementary frame 100 upon a pair of horizontally positioned stub shafts 103, 103 (see Fig. 2), which are rigidly supported upon brackets 104, 104 and removably attached thereto by clamp screws 105, 105; brackets 104, 104 being formed integral with the top plate 72 of turntable 71. As shown in Fig. 3 the casing 101 may be an enclosing field frame of a flame proof motor with the journal bearings 102, 102 at the rear end sides of the motor itself.

As clearly seen by reference to Figs. 1 and 2 of the drawings, the supplementary frame 100 also includes a gear casing 106, the rear end of which is bolted to the front end of the motor casing 101 by bolts or screws 107. The gear casing 106 is also provided with a removable cover plate 108. Said supplementary frame 100 further includes a downwardly sloping elongated neck 109, which is formed integral with the gear casing 106.

To provide for the adjustment of the supplementary frame 100 with respect to the turntable 71 about the horizontal axis provided by the stub shafts 103, 103 there is provided adjacent each side thereof an arm 110, one end of which is journaled to the outer end of the stub shaft 103, as clearly seen in Fig. 2 of the drawings, and is pivotally attached to said stub shaft 103 by bolt and washer means 111. The forward end of each arm 110 is bolted to the gear casing 106 by bolts or screws 112.

Positioned between each of the arms 110 and the motor casing 101 is a pivotal hydraulic piston type motor 113. Said motors 113 are substantially of identical construction and one of them is shown in detail in Fig. 4 of the drawings to which attention is now directed. Said motor 113 comprises a cylinder 114 provided with pivot trunnions 115 and 116. The trunnion 115 is journaled in an appropriate journal bearing in arm 110 which journal bearing is provided with a grease fitting 117 and trunnion 116 is journaled in an appropriate journal bearing carried by stub cylinder 118 formed rigid with a vertical side wall of the motor casing 101, best seen in Fig. 4.

Within the cylinder 114 is a sleeve 272 which is held rigidly in place between end gaskets by removable head 273 attached to cylinder 114 by screws 274. Within the sleeve 272 is a piston 275 provided with a piston ring 276 and a felt packing ring 277 held in place by a removable bronze cap 278 which is attached to the piston 275 by screws 279. Rigidly attached to the piston 275 is a piston rod 280 the lower end of which is recessed at 281 to receive a pivotally attached bearing knuckle 282 which rides on a bearing cup 283. Knuckle 282 and cup 283 have contacting spherical bearing surfaces and said knuckle is pivotally attached to the lower recessed end of piston rod 280 by transversely extending pin 284. The knuckle 282 is permanently attached to the top plate 72 of turntable 71, as by welding, or it may be screw threadedly attached thereto.

To provide for lubrication of the spherical bearing surfaces between knuckle 282 and bearing cup 283 said knuckle 282 is provided with a bore 285 which communicates with a bore 286 in top plate 72 with which is associated a grease fitting 287.

The head 273 is provided with a packing ring 288 which cooperates with the piston rod 280 to provide an oil-tight sliding seal.

The piston motors 113 are of the double acting type and thus inlet ports 289 and 290 are provided adjacent the piston rod end and the head end, respectively, of the cylinder 114 so that the supplementary frame 100 can be moved positively about the horizontal pivotal axes provided by stub shafts 103 in either direction.

Attention is now directed to Figs. 2, 3 and 4 and to the structure of the electric motor carried by the supplementary frame 100 and particularly to the cooling means for said electric

motor. Within the motor casing or housing 101 there is provided an armature 121 mounted for rotation in spaced bearings 122 and 123, the former of which is carried by the front wall 124 of said casing 101 and the latter of which is carried by the rear wall 125 thereof. The armature 121 also includes a shaft 126 to which is keyed a drive pinion 127.

Adjacent its rear end the armature shaft 126 carries a centrifugal fan rotor 128 which rotates in an opening 129 in a partition wall 130. The opening 129 provides an inlet for the fan rotor 128, the outlet for which is provided by a pair of spaced ports 131 in the upright side walls of the casing 101. The ports 131 lead to cooling passageways outside the motor casing 101 provided by longitudinally extending U-shaped plates 132 which provide air cooling passageways from the rear end of the motor casing 101 to the front end thereof.

Adjacent the front end of said motor casing 101 there is provided a plurality of inlet ports 233 which provide a return path for the cooled air from the cooling passageways to the interior of the motor casing 101. It is thus evident that the fan rotor 128 will operate to circulate air over two continuous paths, drawing the air from within the motor casing 101 and circulating it through cooling passageways outside said motor casing 101 as provided by the plates 132 and then returning the cooled air to said motor casing 101.

It is additionally to be noted that the rear wall 125 is provided with a plurality of cooling vanes or ribs 133 which aid in dissipating the heat of the motor.

It is also to be noted by particular reference to Fig. 4 of the drawings, that the plates 132 perform the additional function of acting as bracing supports for the stub cylinders 118.

In addition to those elements previously described, it may be mentioned that the electric driving motor within the casing 101 also includes field structure 134, field coils 135 and commutator 136 which has associated with it the usual brushes, which are not illustrated in the interest of clearness but which are supported by brush supports 137. In this connection it is also to be noted that the partition wall 130 not only acts to direct the inner air to the fan rotor 128 but also acts as a support or base for the brush supports 137.

It is evident that as the armature 121 rotates, fan rotor 128 operates to draw air across the heat developing coils in armature 121 as well as field coils 135 and the commutator 136. This warm air is then thrown laterally through the two openings 131 and will of course impinge against the plate 125 which will dissipate heat particularly through the ribs 133 as well as by virtue of its direct contact with atmosphere. The warm air flowing through openings 131, 131 passes forwardly through the conduits formed by plates 132, 132, which conduits will dissipate a considerable amount of the heat from the flowing air whereupon the cooler air will be returned to the interior of motor casing 101 through inlet ports 233.

It is thus seen that this electric motor is of the totally enclosed type. The function of this electric motor is solely that of driving the kerf cutting mechanism 160 of the mining machine so that this driving is entirely independent of any other operating functions thereof. The kerf cutting mechanism 160 is universally adjustable

as is disclosed in full detail in our parent application above identified, and one of the adjustments which is of importance is provided by virtue of the supplementary frame 100, of which the motor casing or housing 101 forms an integral part, the gear housing 103 and integral neck 109 also forming a part thereof and being rigidly attached to motor housing 101 as above described.

Furthermore, as above described, this supplementary frame 100 is adjustable about a horizontal axis about the rear end thereof provided by the stub shafts 103, 103 and cooperating mechanism by which said supplementary frame 100 is pivoted to the turntable 71 for adjustment on a horizontal axis. This vertical swinging movement of the supplementary frame 100 is provided by the two hydraulic piston motors 113 described in detail above.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In a mining apparatus, a totally enclosed electric motor comprising an enclosing frame, 30 rotary motor mechanism in said frame, longitudinally extending U-shaped plates secured to opposite sides of said frame to provide external air cooling passageways, air inlet and outlet ports leading from said frame interior to said passageways and from said passageways to said frame interior, and pivot bearing means extending laterally from said frame through said passageways and reinforced by being secured to said plates.

2. In a mining apparatus, an enclosed electric 40 motor comprising an enclosing frame, rotary motor mechanism in said frame, mechanism affording an external air cooling passageway, air inlet and outlet ports leading from the frame interior to said passageway and from the latter to 45

the frame interior, and pivot bearing means extending laterally from said frame and reinforced by being secured to the aforesaid mechanism.

3. In a mining apparatus, an enclosed electric 5 motor comprising a rotor and an enclosing housing therefor, a partition extending across said housing and having an opening therein, a fan rotor associated with said opening for forcing air therethrough to secure circulation of air over said rotor, heat radiating means comprising air passageways extending along said housing and communicating with the interior of said housing to provide a circulatory path for air operated on by said fan rotor, and bearing means for said 10 motor housing reinforced by being secured to said heat radiating means.

4. In a mining apparatus, an enclosed electric 15 motor comprising a rotor and an enclosing housing therefor, a transverse partition adjacent one end of said motor housing and having an opening therein, a fan rotor associated with said opening and driven by said rotor to circulate air through said housing over said rotor and through said opening, mechanism extending longitudinally 20 along the outside of said housing to afford a passageway for such circulated air, and pivot bearing means extending laterally from said housing through said passageway and reinforced by being secured to the aforesaid mechanism.

5. In a mining apparatus, an enclosed electric 25 motor comprising an enclosing frame, a rotor in said frame, air circulating fan means driven by said rotor, mechanism providing an air cooling passageway outside said enclosing frame, air inlet and outlet ports leading from the frame interior to said passageway and from the latter back to the frame interior through which passageway air is forced by said fan means through said frame interior, and pivot bearing means extending laterally from said frame and reinforced by being secured to the aforesaid mechanism.

ROBERT K. JEFFREY.

RICHARD D. NICHOLS,
